UNITED STATES PATENT OFFICE.

CHARLES PERRY WILLSON, OF SUMMIT POINT, WEST VIRGINIA.

CAR-COUPING.

SPECIFICATION forming part of Letters Patent No. 257,119, dated April 25, 1882.

Application filed March 8, 1882. (No model.)

To all whom it may concern:

Be it known that I, CHARLES PERRY WILLSON, of Summit Point, in the county of Jefferson and State of West Virginia, have invented 5 a new and useful Improvement in Car-Couplings, of which the following is a full, clear, and exact description, reference being had to the annexed drawings, forming part of this specification, in which—

10 Figure 1 is a plan view of the coupling, showing the internal construction thereof. Fig. 2 is a front elevation, partly in section. Fig. 3 is a sectional side elevation, and Fig. 4 is a link.

15 This invention relates to an improvement in car-couplings in which the link is coupled with a draw-head by means of a horizontal pin, which is adapted to be operated from either side of the car. An ordinary straight link may be 20 used in coupling two cars together, if desired, or in case the coupling-bar should be broken. I design, however, to use a spear-headed coupling-bar, which engages vertically with a corresponding bar; and as a means of lifting the 25 bar for this purpose I provide a lever at each side of the draw-head, which is adapted to press the outer end of the coupling-bar upward.

In order that others skilled in the art to 30 which my invention pertains may readily understand the construction and operation of the same, I will now proceed to a detailed description of the several parts thereof.

The draw-head A is provided with a cross-head, B, forming two partially-closed chambers extending from opposite sides of the draw-head, and communicating with the interior of the draw-head by means of apertures a a, through which a pin, b, is made to engage with the link end of the coupling-bar c. The pin b 35 is provided with a conical head, b', at each end, and a neck, b'', forming a shoulder, by means of which a catch, d, arranged in each chamber of the cross-head, shall be adapted to withdraw the pin from engagement with the link or coupling-bar on either side of the draw-head.

40 The catch d consists of a head, d', having a recess, d'', in its under surface to receive the conical head of the pin, and a pivoted jaw, d'', having a smaller recess in its under surface, 45 adapted to engage with the neck of the pin and prevent the head thereof from escaping from the recess d'' when the catch is drawn

back by means of its rod d''. The rod d'' projects through an opening in the end of cross-head B, and has a spring, e, coiled about it on the inside of the chamber, which tends to hold the catch with sufficient force against the draw-head to cause the jaw d'', which is beveled at the end, to be partially raised through an opening, e', in the top of its inclosing-chamber. 55 The top of the chamber is so constructed that at the instant the catch is drawn back it will press the jaw downward to engage with the pin, and the chamber is provided with stops f to limit the withdrawal of the catch and prevent the spring from being too greatly compressed.

Underneath the cross-head B, on each side of the draw-head, is fulcrumed a lever, g, the inner end of which is pivoted in a slot, i, formed 70 in the lower end of a bar, j, which is arranged vertically in an opening, k, in the draw-head. The said bar is located slightly forward of the coupling-pin b, so that when the bar is pressed upward by either of the levers g it will lift the 75 coupling-bar c to cause it to engage with a corresponding bar in coupling two cars together.

The coupling-bar c has something of the form of an arrow-head, with the upper shoulder made 80 convex from side to side and the under shoulder correspondingly concave, so that the upper shoulder of one head shall engage with the under shoulder of another. An additional concave shoulder is formed on the under side 85 of the bar facing the first-mentioned concave shoulder, which serves as a guide for the corresponding head in coupling. As this coupling-bar has already been patented to me, it is 90 not claimed in the present application.

By arranging an ordinary straight link, l, in a vertical position it may be substituted for the coupling-bar c in case the latter should be broken, and with a view to such an emergency I design that such a link shall be carried in 95 some convenient recess where it may be readily available when needed. For lifting the bar c from the top of a car, a cord or chain may be attached thereto and secured where it can be reached.

The link l, by means of perforations in its ends, may be coupled vertically, if desired, by inserting the pin b in the perforation m.

Having thus described my invention, what I

claim as new, and desire to secure by Letters Patent, is—

1. In a car-coupling, a horizontal pin adapted to engage with a vertical link, in combination with catches for engaging with and operating the pin from either side of the car, substantially as shown and described.

2. In a car-coupling, a coupling-pin having a conical head and a neck at each end, in combination with automatic catches adapted to be operated from either side of the car, and means for supporting said pin and catches, substantially as shown and described.

3. In a car-coupling, the combination, with the double-headed coupling-pin, of the spring-actuated catches having recesses for receiving the heads of the pin and pivoted jaws for retaining said heads, and a cross-head for supporting the catches, substantially as shown and described.

4. In a car-coupling, the combination, with a draw-head, of a cross-head having chambers on each side the draw-head, and spring-actuated sliding catches having beveled retaining-jaws, the chambers being formed with openings at the top, near the draw-head, to allow oscillation of the jaws, substantially as shown and described. 25

5. In a car-coupling, the combination, with the arrow-headed coupling-bar, of the vertical bar and levers for operating said bar to lift the outer end of the coupling-bar, substantially as shown and described, and for the purpose set forth. 30

CHARLES PERRY WILLSON.
